CLAIM

The ornamental design for a charging set, as shown and described.

DESCRIPTION

FIG. 1 is a front perspective view of a charging set according to the present design, shown in an assembled configuration. FIG. 2 is a rear perspective view of the charging set, shown in an assembled configuration.

FIG. 3 is a rear perspective view of the charging set, shown in a disassembled configuration.

FIG. 4 is a top elevation view of the charging set, shown in an assembled configuration.

FIG. 5 is a front elevation view of the charging set, shown in an assembled configuration.

FIG. 6 is a right side elevation view of the charging set, shown in an assembled configuration, the left side elevation view being a mirror image thereof.

FIG. 7 is a rear elevation view of the charging set, shown in an assembled configuration.

FIG. 8 is a bottom elevation view of the charging set, shown in an assembled configuration.

FIG. 9 is a front perspective view of a cable holder component of the charging set, shown separately for ease of illustration.

FIG. 10 is a rear perspective view of the cable holder component of the charging set, shown separately for ease of illustration.

FIG. 11 is a top elevation view of the cable holder component of the charging set, shown separately for ease of illustration, the bottom elevation view being identical thereto.

FIG. 12 is a front elevation view of the cable holder component of the charging set, shown separately for ease of illustration, the rear elevation view being identical thereto.

(Continued)

FIG. 13 is a right side elevation view of the cable holder component of the charging set, shown separately for ease of illustration, the left side elevation view being identical thereto.

FIG. 14 is a front perspective view of a charging component of the charging set, shown separately for ease of illustration. FIG. 15 is a rear perspective view of the charging component of the charging set, shown separately for ease of illustration. FIG. 16 is a top elevation view of the charging component of the charging set, shown separately for ease of illustration. FIG. 17 is a front elevation view of the charging component of the charging set, shown separately for ease of illustration. FIG. 18 is a right side elevation view of the charging component of the charging set, shown separately for ease of illustration, the left side elevation view being a mirror image thereof.

FIG. 19 is a rear elevation view of the charging component of the charging set, shown separately for ease of illustration. FIG. 20 is a bottom elevation view of the charging component of the charging set, shown separately for ease of illustration.

FIG. 21 is a front perspective view of a left side of a cord component of the charging set, shown separately and broken away for ease of illustration.

FIG. 22 is a front perspective view of a right side of the cord component of the charging set, shown separately and broken away for ease of illustration.

FIG. 23 is a top elevation view of the cord component of the charging set, shown separately for ease of illustration.

FIG. 24 is a front elevation view of the cord component of the charging set, shown separately for ease of illustration, the rear elevation view being identical thereto.

FIG. 25 is a right side elevation view of the cord component of the charging set, shown separately for ease of illustration. FIG. 26 is a left side elevation view of the cord component of the charging set, shown separately for ease of illustration; and,

FIG. 27 is a bottom elevation view of the cord component of the charging set, shown separately for ease of illustration.

The broken lines in the drawings illustrate elements of the charging set that form no part of the claimed design.
